UNITED STATES PATENT OFFICE.

NIELS P. BACH, OF MILLBURN, NEW JERSEY, ASSIGNOR TO THERMOKEPT CORPORATION, OF NEW YORK, N. Y., A CORPORATION OF DELAWARE.

CAN.

Application filed February 2, 1924. Serial No. 690,139.

To all whom it may concern:

Be it known that I, NIELS P. BACH, a subject of the King of Denmark, residing at Millburn, in the county of Essex and State of New Jersey, have made a certain new and useful Invention in Cans, of which the following is a specification.

This invention relates to improvements in cans, and in particular to that class of cans which are opened by tearing a strip of metal from the can body by rolling it on a key to thereby open the can.

It is one of the prime objects of my invention to facilitate the removal of said opening strip and to secure clean-cut, smooth edges as the strip is removed and the can opened.

Another object includes the provision of a can body blank which is provided with parallel scorings, or weakened regions, on either side or on both sides of the metal sheet to provide the removable strip in the sealed can.

To further render the removal of the scored opening strip absolutely reliable, I provide secondary parallel scorings which lie within the main scorings and serve to prevent the opening strip from running out due to faulty and insufficient scoring, or to other causes, as grossly uneven rolling of the metal on the key.

A still further object includes the provision of a simple can blank which is provided with a weakened area, at no material increase of cost in production, and whereby the can is opened with certainty and dispatch.

Other objects will appear hereinafter, and I attain these objects by the construction illustrated in the accompanying drawing, in which:

Fig. 1 is a view in elevation of a can which is made in accordance with the principles of my invention.

Fig. 2 is a view taken on lines 2—2 of Fig. 1, looking in the direction of the arrows.

Fig. 3 is a edge view of a portion of the can body blank which is provided with parallel scorings in accordance with my invention.

Fig. 4 is a plan view of a portion of the blank, showing the under lap-seam portion.

Fig. 5 is a view similar to that of Fig. 4 but showing the outer lap-seam portion and the extending key lip.

Fig. 6 is a view showing a slightly modified form of construction and taken on lines 6—6 of Fig. 7.

Fig. 7 is a view similar to that shown in Fig. 4, but illustrating the double parallel scoring as applied to the can body.

Fig. 8 is a view similar to that shown in Fig. 5, but illustrating the double scoring as it is applied to the can body.

Like numerals refer to similar parts throughout the several views.

It has been proposed to overcome the inconvenience and difficulty of opening sealed cans by use of an opening key, but one of the chief drawbacks to key opened cans is found to reside in the tendency of the opening strip to run out and tear off before the can is opened, and it is the purpose of my invention to provide simple but efficient means to overcome this defect.

To this end I provide the can blank 10, from which the can body 11 of the finished can is made, with parallel scorings 12, 12 and 13, 13. In a preferred form, to which, however, I do not desire to be limited, scorings 12, 12 are parallel and of the desired distance to form the proper width for an opening strip 14. If scorings 12, 12 are formed on the surface of the metal which forms the outer surface of the finished can, then scorings 13, 13 are formed on the side of the metal which forms the inner surface of the can. In any event are the parallel scorings 12, 12 and 13, 13 directly opposite each other and of such depth as to insure safe and absolute removal of the strip when the can is to be opened. The opening is conveniently accomplished by the conventional key 15 being applied to the tongue 16 of strip 14 and turned to roll the weakened opening strip 14 on the key.

To facilitate starting the strip to roll properly, I provide notches 17 at the beginning of the weakened area. By thus providing a can body with oppositely placed or double parallel scorings, I am enabled to quickly, easily and with certainty open a sealed can and at the same time leave the edges thus formed practically smooth and without sharp projections.

- Cans that are thus opened form covers 18 whereby the weakened scored area is easily 55 removed to open the sealed package.
3. A sealed package in the form of a can having double and parallel scorings within and without to form a weakened area, and a tongue extending beyond said scorings 60 whereby the weakened scored area is easily removed to open the sealed package.
4. A sealed package provided with scorings, within and without the can to form a weakened strip, and means for removing 65 said weakened strip.
5. A sealed package provided with double scorings within and without the can to form a weakened strip, and means for removing 70 said weakened strip.
6. A body blank for cans, comprising a sheet having parallel scorings on one side and correspondingly placed parallel scorings on the opposite side to form a weakened strip. 75
7. A body blank for cans, comprising a metal sheet having a tongue extension, notches cut into an edge of said sheet adjacent said tongue, and parallel scorings extending across said sheet on its opposite sides. 80
8. A body blank comprising a metal sheet, a tongue extending from one edge of said sheet, said blank having a notch on each side of the tongue near the edge of the sheet, and double scorings extending from said notches across the sheet on opposite sides of said sheet. 85
9. A body blank comprising a metal sheet, a tongue extending from one edge of said sheet, said blank having a plurality of V-shaped cuts lying in a plane substantially at right angles to the blank surface. 90
10. A body blank comprising a sheet cut to form the walls of a container, a tongue 95 extending from one edge of the sheet, said sheet being provided with notches in one edge thereof at the base of the tongue, and weakened depressions in both surfaces of said sheet, said depressions lying in substantially parallel planes, by passing through said notches and being perpendicular to the surface of said sheet. 100
- In testimony whereof I have hereunto set my hand on this 30th day of January A. D. 105 1924.
- NIELS P. BACH.
